UNITED STATES PATENT OFFICE

152,323

DESIGN FOR AN ELECTRIC HEATER FOR DENTAL IMPRESSIONS OR THE LIKE

Harold P. Chapman, Columbus, Ohio

Application August 7, 1946, Serial No. 132,348

Term of patent 14 years

(Cl. D81—10)

To all whom it may concern:

Be it known that I, Harold P. Chapman, a citizen of the United States, residing at Columbus, in the county of Franklin and State of Ohio, have invented a new, original, and ornamental Design for an Electric Heater for Dental Impressions or the like, of which the following is a specification, reference being had to the accompanying drawing, forming a part thereof.

Fig. 1 is a top plan view of an electric heater for dental impressions or the like, showing my design;

Fig. 2 is a side elevational view thereof.

I claim:

The ornamental design for an electric heater

for dental impressions or the like, substantially as shown.

HAROLD P. CHAPMAN.
